DIE FOR FORMING UNDERCUT CASTINGS

Louis H. Morin, Bronx, N. Y.

Application July 1, 1944, Serial No. 543,171

10 Claims. (Cl. 18—42)

1

This invention relates to dies for forming die castings having undercut surfaces thereon. More particularly, the invention relates to dies of the class described wherein undercut recesses are formed in at least one surface of the resulting casting without the use of cores and in a two-part die structure, particularly wherein the dies are mounted for swinging or arcuate movement, in order to eject the casting from the die cavities. The novel features of the invention will be best understood from the following description when taken together with the accompanying drawing, in which certain embodiments of the invention are disclosed, and in which the separate parts are designated by suitable reference characters in each of the views; and in which:

Fig. 1 is a diagrammatic view showing three coupled scoops of separable fastener stringers in cross section, indicating one type of scoop structure made with my form of dies which I employ.

Fig. 2 is a view similar to Fig. 1, showing another form of scoop structure produced from different dies than those employed in producing the scoops of Fig. 1.

Fig. 3 is a sectional view on the line 3—3 of Fig. 2, showing only the surface section of the scoops, as seen in Fig. 2, simply to indicate the longitudinal contour of scoops made with the dies employed.

Fig. 4 is a diagrammatic sectional view showing a pair of dies mounted to swing about a common axis in forming scoops of the type and kind illustrated in Fig. 1, and omitting the tape on which the scoop is formed.

Fig. 5 is a view similar to Fig. 4, showing dies in an open position.

Fig. 6 is a partial section on the line 6—6 of Fig. 4, and also illustrating the stringer tape upon which the scoop is cast.

Fig. 7 is a view similar to Fig. 4, showing dies pivoted upon spaced axes for producing scoops of the type and kind illustrated in Fig. 2, and also omitting the tape on which the scoop is formed.

Fig. 8 is a view similar to Fig. 7, showing the dies in an open position; and

Fig. 9 is a section on the line 9—9 of Fig. 7, and showing the scoop cast on a stringer tape.

In the accompanying drawing, the dies illustrated have cavities for forming scoops of separable fastener stringers, and particularly what I term coreless scoops. That is to say, scoops which are die cast directly upon the stringer tapes by the use of a pair of swinging dies with-

2

out utilizing core pins or other core members for forming the undercut or recessed portions of the scoops in producing the female coupling of the scoops, preventing transverse separation of coupled scoops.

In the construction of dies prior to recent developments by me, it has been impossible to form undercuts in die cast, molded or otherwise formed products without the use of multiple dies or cores movable relatively to the dies. In more recent developments by me, I have conceived dies having cavities which will form undercuts in the resulting products by either moving the dies angularly to each other in ejecting the product from the dies, or by so forming the undercut surfaces and other surfaces of the dies, as to facilitate automatic ejection of the casting and movement of the casting relative to dies which are separated in a common plane in the manner of conventional die movement.

The present application deals with the production of dies which will swing in an arcuate path or about one or more axes in separation of the dies and in freeing the casting or product from the cavity or impressions of the dies in order to form undercut recesses or channels in predetermined surfaces of the resulting products. The method of forming castings with such dies is described and claimed in a copending application Serial Number 543,170, filed July 1, 1944 now abandoned.

In Figs. 4, 5 and 6 of the drawing I have shown a pair of dies 10 and 11 having interfitting bearing portions as at 12, to swing about a common axis in the form of a shaft or rod 13. Both dies 10 and 11 have registering cavities 14 and 15 on adjacent surfaces thereof which in the construction shown, are the same cross sectional form as well as longitudinal sectional form. In cross sectional form, the combined cavities 14 will form at the upper surface of the resulting casting 16 a longitudinal recess 17, the radius of which is common with the axis 13. In other words, the walls 18 and 19 of the cavities 14 and 15 have a curvature concentric with the swinging movement of the die parts 10 and 11 on the axis 13. Opposed walls 20 and 21 of the cavities 14 and 15 are also curved and are preferably of a radius common to or slightly less than the radius of the walls 18 and 19, so that the convex surface 22 of the casting is free to fit and operate in the concave surface 17 of an adjacent casting, as will appear from a consideration of Fig. 1 of the drawing.

In other words, the convex surfaces 22 of

coupled scoops seat and operate in the concave surfaces 17 of adjacent scoops, and the slight difference in curvatures provides a free bending of the stringer tapes one upon the other, the structure being more or less of a modified ball and socket coupling between the scoops. This engagement of the scoops also retains coupled scoops against transverse separation, as will clearly appear from a consideration of Fig. 1 of the drawing.

The scoops 16 are held against lateral separation by more or less diamond shaped heads 23, the upper and lower projections 24 of which will engage upper and lower recesses 25 of adjacent scoops, as will clearly appear from the longitudinal section of the scoop, as seen in Fig. 6 of the drawing. It will here be kept in mind that the irregular longitudinal contour of the scoop, as seen in Fig. 6, is carried out to both sides of the scoop in transverse parallel lines, so that there is no wall structure on the scoop interfering with the swinging separation of the dies 10 and 11 in ejecting the casting. The section in Fig. 6 of the drawing is taken through the head portion 23 of the scoop, as seen in Fig. 6, whereas in Fig. 1, a section through the recessed portion 25 thereof is seen in the middle scoop of said figure. By employing a slightly less radius on the surfaces 22 of the scoops, it will be apparent that these convex surfaces converge to a degree with the concave surfaces 17, thus providing a free separation of the dies one from the other.

In Fig. 6 of the drawing I have shown at 26 the gate opening on the parting line of the dies through which casting material is injected into the cavities from a nozzle part of which is diagrammatically shown at 27. In this figure is also indicated at 28 a part of a stringer tape upon which the casting is formed, and at 29 is indicated one of a pair of grippers employed to engage the tape to support the tape and casting in the separation of the dies and also to feed a formed casting into a lowered position, as indicated in dotted lines at 30 in Fig. 4, in order to form the next successive casting on the stringer tape 28. This operation is continued indefinitely until the required number of castings are formed in defining each stringer length.

In Figs. 7, 8 and 9 of the drawing I have shown at 31 and 32 a pair of similar dies mounted for swinging movement upon independent and spaced axes 33 and 34. The dies 31 and 32 have cavities 35 and 36 adapted to collectively form cast scoops 37 of the type and kind illustrated in Fig. 2 of the drawing. These castings are of the same longitudinal section as the castings 16, as will appear from a consideration of Fig. 9. In other words, they will include outer heads 38 similar to the heads 23, inwardly of which are the opposed recesses 39.

In Fig. 9, 40 represents the gate opening similar to the gate 26, 41 part of the injection nozzle, similar to the nozzle 27, and 42 the stringer tape upon which the casting 37 is formed. Grippers are also employed, and one of these grippers is indicated at 43.

The cast scoops 37 differ from the scoops 16 in providing sharp ridges 44 on the convex surfaces of the scoops and corresponding recesses 45 on the opposed or undercut surfaces of the scoops. This result is produced by providing walls 46 and 47 in the cavities 35 and 36 which are concentric to the swinging movement of the dies 31 and 32 on their pivots, the walls inter-

secting on the parting line of the dies to form the ridges 44 in each casting. The cavities 35 and 36 have opposed curved surfaces 48 and 49 preferably of a radius greater than the radius of the surfaces 46 and 47 and also intersecting on the parting line of the dies to form the longitudinal groove, recess or channel 45 in each casting. It may be noted that the radius of curvature of surfaces 48 and 49 of dies 31 and 32, respectively, is less than the distance to such surfaces from the pivot centers 33 and 34, about which each die 31 and 32 moves.

It will be understood that the walls 48 and 49 could be parallel to the walls 46 and 47 but by contracting these walls, the corresponding surfaces on the castings formed will converge to the sides thereof and produce between coupled scoops of two stringers spaces as at 50, note Figs. 2 and 3, which will provide free bending or flexing movement of coupled stringers. The clearances as at 50 are materially greater than the slight clearance shown in Fig. 1, and this is due to the fact that the ball and socket structure in itself, as shown in Fig. 1, provides for free flexing or bending movement of the stringers.

The walls of the die cavities above defined, in other words, the walls 46 and 47, produce the curved converging walls 51 and 52 on the resulting scoops, whereas the walls 48 and 49 produce the walls 53 and 54 of the scoops. These walls carry the longitudinal irregular cross section shown in Fig. 9 throughout the full width of the scoops.

It will be apparent that dies of the general type and kind herein disclosed may have cavities of any shape or form to produce products of any kind consistent with the formation of undercut recessed portions on at least one surface of the resulting products. Further, the illustration in the accompanying drawing of the methods of controlling movement of the dies is only illustrative of two adaptations of the invention. Any means may be employed to guide the dies in a curved or arcuate path, or parallel to at least one surface of the die and the resulting product and capable of freeing an opposed surface by reason of the relative contour or curvature of such opposing surface. It is also desirable, for free ejection of a casting, to have these opposing surfaces of the die cavity and the resulting product converging in the direction of the side surface of the product, or in other words, converging with respect to the depth of the cavity. Another way of explaining this structural feature would be to say that the product formed between two dies would have its greatest thickness at the parting line of the dies.

In referring to the formation of die castings, it will be understood that any types and kinds of materials may be employed in the sense of metallic or plastic materials, and in molding or forming processes of any type or kind wherein it is practical to form products in die cavities or impressions by movement of the dies toward and from each other in curved paths, and particularly in separation of the dies by such movement to eject the castings or molded products from the die cavities. In the accompanying drawings, the castings are shown as formed on a mounting, such for example, as the stringer tape. In many instances, no mountings will be employed.

Having fully described my invention, what I

claim as new and desire to secure by Letters Patent is:

1. A pair of coreless dies for forming die castings of concavo-convex cross sectional contour throughout the length thereof to provide on one surface of the castings undercut recesses longitudinally thereof, said dies collectively having a cavity of said concavo-convex cross sectional contour throughout the length of the cavity and opening through adjacent surfaces of the dies, the walls of each die cavity being of irregular contour longitudinally thereof, the walls of the cavity defining the irregular contour being parallel in each cavity, and said dies being mounted for separating movement on a common axis with which that wall of the cavity forming the concave contour of the casting is concentric.

2. A die for shaping a predetermined product having an undercut recess on one surface defined by curved walls, said die comprising two die parts, each die part having an impression, the impressions of the die parts registering on the parting line of the dies, each impression having undercut surfaces extending beyond the limits of the registering portions of said impressions at the parting line to form in the product shaped by said die impression the undercut recess in one surface of said product, said dies being movable in curved paths to free the dies from the undercut surface of the product in the separation of said dies, and the movement of said dies being on independent and spaced axes.

3. A pair of coreless dies for forming die cast separable fastener scoops; said dies having registering cavities and mating faces and each die having a cavity opening in such face bounded by parallel edge portions merging successively into converging, diverging and again converging edge portions; each cavity opening lying entirely within the confines of the mating face; each cavity presenting transverse sections, at right angles to the plane of the cavity opening, all bounded by an inner wall spaced from and substantially parallel to the die face and upper and lower similar arcuate walls; said cavities together defining a complete die cast scoop when the cavity openings are in registry; and each of said dies being mounted for separating movement about a fixed pivot center located above said upper arcuate walls, the radius of curvature of said upper arcuate wall of each die being equal to the distance to such wall from the pivot center about which each such wall moves, and the radius of curvature of said lower arcuate wall of each die being less than the distance to such wall from the pivot center about which each such wall moves.

4. A pair of coreless dies for forming die cast separable fastener scoops, said dies having registering cavities and mating faces and each die having a cavity opening lying entirely within the confines of the mating face; said cavities together defining a complete die cast scoop when the cavity openings are in registry; each cavity being bounded by upper and lower arcuate walls; each die having a channel opening through one end thereof and extending inwardly to the die cavity, each said channels together forming a gate passage when the dies are in registering position; and each of said dies being mounted for separating movement about a fixed pivot center located above said upper arcuate walls, the radius of curvature of said upper arcuate wall of each die being no greater than the distance from the pivot center of such die to any

point on said upper arcuate wall and the radius of curvature of said lower arcuate wall of each die being no greater than the distance from the pivot center of such die to any point on said lower arcuate wall.

5. A pair of dies for forming die cast separable fastener scoops, said dies having cavities and mating faces and each die having a cavity opening in such face bounded by parallel edge portions merging successively into converging, diverging and again converging edge portions, each cavity presenting transverse sections, at right angles to the plane of the cavity opening, all bounded by an inner wall spaced from and substantially parallel to the die face and upper and lower similar arcuate walls, and said dies being mounted for separating movement about two, spaced, fixed, pivot centers located above said upper arcuate walls.

6. A pair of dies for forming die cast separable fastener scoops, said dies having cavities and mating faces and each die having a cavity opening in such face bounded by parallel edge portions merging successively into converging, diverging and again converging edge portions, each cavity presenting transverse sections, at right angles to the plane of the cavity opening, all bounded by an inner wall spaced from and substantially parallel to the die face and upper and lower similar arcuate walls, and said dies being mounted for separating movement about two, spaced, fixed, pivot centers located above said upper arcuate walls, the center of curvature of each upper arcuate wall substantially coinciding with the pivot center of such wall.

7. A pair of dies for forming die cast separable fastener scoops, said dies having cavities and mating faces and each die having a cavity opening in such face bounded by parallel edge portions merging successively into converging, diverging and again converging edge portions, each cavity presenting transverse sections, at right angles to the plane of the cavity opening, all bounded by an inner wall spaced from and substantially parallel to the die face and upper and lower similar arcuate walls, and said dies being mounted for separating movement about two, spaced, fixed, pivot centers located above said upper arcuate walls, the radius of curvature of said arcuate walls of each die being no greater than the distance from each pivot center to any point on either of the arcuate walls which move about such center.

8. A coreless die for forming die castings having an undercut recess on one surface thereof, said die comprising two die parts having adjacent abutting surfaces, said die parts each having registering cavities which have openings in said abutting surfaces and which are defined by walls extending into each die part inwardly of said surfaces, said cavity openings lying entirely within the confines of said abutting surfaces, said walls of the cavities of the die parts which define the undercut recess in the casting converging and intersecting at said abutting surfaces, and said die parts being mounted to swing on spaced independent axes.

9. A coreless die for forming die castings having an undercut recess on one surface thereof, said die comprising two die parts having adjacent abutting surfaces, said die parts each having registering cavities which have openings in said abutting surfaces and which are defined by walls extending into each die part inwardly of said surfaces, said cavity openings lying en-

tirely within the confines of said abutting surfaces, each of said die parts being mounted for separating movement about a fixed axis, said walls of the cavities of the die parts which define the undercut recess in the casting converging and intersecting at said abutting surfaces, and other opposed walls defining the die cavities being concentric with respect to the axis of each die part.

10. A die comprising a pair of die parts having registering cavities in adjacent sides of said parts, each of said cavities having curved walls defining concave and convex surfaces on opposite sides of each said cavities, said concave and convex surfaces converging in the direction of the depth of their respective cavities, said die parts being mounted on independent axes and movable relatively to each other in a di-

rection which parallel the curvature of one of their said curved walls.
